CARGO CRANE

Nils Peter Erik Andersen, Elm Grove, Wis., assignor to Harnischfeger Corporation, Milwaukee, Wis., a corporation of Wisconsin

Application February 18, 1943, Serial No. 476,351

8 Claims. (Cl. 214—15)

This invention is concerned with apparatus formed as a self-contained part of a ship and adapted for loading and unloading cargo. It resides, more specifically, in a specialized traveling bridge crane having the novel property of being adapted to be raised from a stowed position close to the deck to an operating position on overhead athwartship runways extendable beyond the sides of the ship. The several parts of the apparatus are so related that the bridge of the crane which is longitudinally disposed with respect to the ship may be transversed athwartship to and from positions above the hatch and beyond the sides of the ship. The traveling bridge also is provided with hoisting mechanism movable longitudinally thereof from which hoisting lines may be dropped for lifting and lowering loads through the hatch or over the side of the vessel at various positions throughout the length of the bridge.

It has long been recognized that the traveling overhead type of crane has marked advantages from the standpoint of rapid handling and precision of control and numerous efforts have been made to adapt cranes of this type to the handling of cargo in the loading and unloading of vessels. Some of these proposed arrangements have included the traveling overhead crane as a part of the structure of the vessel itself. For several reasons these latter attempts have not proven successful, although cranes of the type mentioned, installed as a part of permanent shore facilities, have been successfully used. One of the drawbacks of such equipment, when installed as heretofore proposed upon ships, has been that when the structure has been formed in a sufficiently rigid and durable manner to permit the handling of heavy loads, it has resulted in the placing of heavy weights upon the overhead runways high above the deck, to be carried there while at sea to the detriment of the stability of the vessel. A further drawback has been that the carrying of the heavy parts of the crane in elevated position results in severe wracking stresses due to the motion of the vessel in heavy seas. Some efforts have been made to collapse and lower the entire overhead structure when the crane is not in use. These collapsible structures have suffered from the disadvantage that they do not have sufficient strength to permit the hoisting of the heavy loads for which the overhead type of crane is so well adapted and in addition the expense of rigging and unrigging these arrangements has discouraged their use.

Through the improvement of this invention the

drawbacks of structures previously proposed have been eliminated or substantially reduced, and a firm and substantial overhead runway provided which may be left in place as a permanent part of the vessel without unduly adverse effect upon its stability, and at the same time the heavy parts of the crane, including the bridge and hoisting trolleys and parts of the overhead runway, may be lowered to a position close to the deck of the vessel when the ship is at sea, and may be raised when desired to the level of the overhead runway quickly and simply and at small expense through the use, if desired, of the power of the crane's own hoisting mechanism.

15 This invention is herein described by reference to the accompanying drawings which form a part hereof, and in which is set forth by way of illustration and not of limitation one form in which the apparatus of this invention may be embodied.

In the drawings:

Fig. 1 is a transverse sectional view of a vessel showing in elevation a crane constructed in accordance with this invention;

25 Fig. 2 is a longitudinal view in elevation showing a part of the vessel and the crane set forth in Fig. 1 in section, with the bridge moved to a position above the hatch, fragments of adjacent cranes also appearing;

30 Fig. 3 is a top plan view showing the crane as illustrated in Fig. 1 including fragments of adjacent cranes;

Fig. 4 is an enlarged detailed view in section viewed through the plane 4—4 indicated in Fig. 2, parts also being shown broken away;

35 Fig. 5 is a phantom view in perspective showing the reeving of the rigging by which the bridge assembly may be raised from and lowered to the deck; and

40 Fig. 6 is an enlarged detailed view in section viewed through the plane 6—6 indicated in Fig. 1. While it is contemplated that several cranes of the type shown in the drawings may be mounted upon a single vessel, one for example above each hatch, the drawings herein for purposes of simplicity show but a single crane carried above a single hatch, with fragments only of adjacent cranes. Referring now to the drawings, and

45 partially to Fig. 1 a conventionalized vessel 1, is shown, provided with permanently attached overhead runway supports 2, 3, 4, and 5, rising from the deck 6. The overhead runway supports 2, 3, 4, and 5 carry upon their upper ends, overhead athwartship runway members 7 and 8,

the whole being rigidly joined together and braced by tie members 9. As appears more clearly in Figs. 2 and 3, the overhead runway members 7 and 8 are rigidly joined by a central girder 10, hidden by member 19 in Fig. 1, which further serves to tie the entire overhead structure together into a rigid integral whole. On the opposite side of the hatch 11, in the fore and aft direction and extending athwartship in a similar manner, is an overhead runway structure like the one just described and the corresponding parts thereof are designated by the same numerals as those applied to the runway structure first described.

For the purpose of extending the transverse runways beyond the sides of the vessel, overhanging members 12 and 13 may be provided. These overhanging members are of known construction and may be hinged, if desired, by means not shown and forming no part of this invention, so as to be swung from the position shown into a position in alignment with the rail of the vessel when they are not in use.

Secured along the upper face of the runway members 7, 8, 12 and 13 are rails 14 for carrying the rolling ends of a crane bridge 15. Adjacent the rails 14 are racks 16 with which gears rotatably carried upon the rolling bridge may engage to insure positive control of the movement of the bridge in spite of any listing of the vessel which may occur by reason of the handling of cargo or otherwise. Each of the overhead runways also carries an additional set of racks 17 and rails 18 for the accommodation of similar bridges 15 shown in fragmentary form only.

Between the ends of the runway members 7 and 8 and in alignment with the rails and racks 14, 16, 17 and 18 carried thereon, are elevatable runway sections 19, one for each of the sets of rails and racks 14 and 16 and 17 and 18 so that the same extend continuously across the elevatable sections 19 when in raised position as appears clearly in Fig. 3.

Secured to the inboard faces of columns 3 and 4 are vertical guiding ribs 20, adapted to be slideably engaged by forked ends 21 of the members 19 so that the latter are guided for vertical sliding movement as appears more clearly in Fig. 4. For controlling and effecting this vertical sliding movement a system of hoisting cables to be described hereinafter is provided.

In the particular form of the apparatus herein illustrated and described, the longitudinally extending, traveling bridge 15 is provided with rails upon which two self propelled hoisting trolleys 22 and 23 are carried. Trolleys 22 and 23 are provided with hoisting drums from which hoisting lines 24 and 25 extend downwardly, normally for the purpose of engaging and lifting the various loads to be handled, as for example as appears in Fig. 1. However when the bridge and trolley assembly, including the elevatable runway sections 19, is to be lifted from the position shown in dotted lines in Fig. 1 to the level of the overhead runway or lowered therefrom, the hoisting lines 24 and 25 may be unreeved from blocks 58 and passed downwardly through blocks 26 and 27 respectively, secured to the deck 6 of the vessel, as appears more clearly in Figs. 2 and 5. The hoisting lines 24 and 25 then pass respectively, as appears in Fig. 5, to blocks 28 and 29, likewise secured to the deck 6 of the vessel, and thence through blocks 30 and 31 respectively, to dead end connections 32 and 33 respectively, rigidly attached to the deck 6.

Each of the blocks 30 and 31 engage forked

luff tackles for lifting one of the elevatable members 19. The forked luff tackle engaged by block 30 is made up of cables 33 and 34, while that engaged by block 31 is made up of cables 35 and 36. Considering now the luff tackle engaged by block 30, cable 33 passes first to block 37 secured to the deck 6 near the base of an overhead runway support from which it passes freely upwardly through an aperture in the end of member 19 to a two sheave nest 38 secured in the overhanging end of overhead runway member 8. From there the cable 33 passes to sheave 39 secured to the end of the member 19, and returns to the nest 38 and again passes to the sheave 39 where it is dead ended. In like manner the cable 34 extends through the blocks 40 and 41 to the nest 42 and the sheave 43 at the opposite end of the member 19, to complete the lifting and lowering arrangement for this member. In like manner the other forked luff tackle for raising and lowering the opposite member 19 is reeved by passing its branch cable 35 through the blocks 44 and 45 to the nest 46 and the sheave 47 and by passing the branch cable 36 through the block 48 to the nest 49 and sheave 50. Thus, when the drums of the trolleys 22 and 23 take in cable by winding, the members 19 rise and lift the bridge 15 to the level of the overhead runway. Lowering is accomplished by the opposite motion.

When the members 19 are brought to their extreme upward position in the manner just described, conical seats 51 secured to the overhead runway members 7 and 8 are engaged by conical plug members 52, secured to the vertically movable members 19 as appears particularly at the left hand side of Fig. 4. At the same time bolts 53 pass through the openings provided therefor in the seats 51. With the parts in this position nuts may be run on to the bolts 53 and the member 19 locked rigidly in position. This lock is provided at both ends of the member 19 and in this way the racks 16 as they extend across the juncture between the permanent overhead runway members 7 and 8 and the elevatable member 19 are precisely positioned so that there is no alteration in pitch at the juncture. When the members 19 are to be again lowered the nuts are removed from the bolts 53, and prior to their removal the hoisting lines 24 and 25 are reeved in the manner illustrated in Fig. 5 so as to bear the load otherwise held by the bolts 53. Lowering of the entire structure is then accomplished by paying out cable from the drums on trolleys 22 and 23 until the lower ends of members 19 engage ledges 54 provided as a support for the entire elevatable structure when in lowered position.

Control the various movements of the crane is regulated through control box 55 carried near the middle of the bridge 15 and electrically connected with the several motors in known manner. As shown in Fig. 2, a platform 56 is secured beneath the control box 55 for the accommodation of the operator, from which position he may observe the load as it is lifted from the hold as well as when it is being handled on the dock 57 beyond the side of the vessel. The control platform 56, however, because of its downward projection interferes, when in normal position, with the lowering of the bridge 15 to the position intended. For this reason platform 56 is divided along its center line and pivotally mounted at its upper corners so that it may be swung to the position indicated by dotted lines in Fig.

2 when the bridge 15 is in its lowered position.

While, for the purpose of convenience and simplicity of construction, it is desirable to employ the hoisting mechanism of the trolleys 22 and 23 themselves for the purpose of raising and lowering the elevatable portions of the structure in the manner described, it is contemplated that a separate winch or winches may be employed for this purpose, or that other equivalent elevating means such as screws or hydraulic hoists may be employed to raise or lower the members 19. It is also apparent that either one of the trolleys 22 or 23 may be employed singly through appropriate reeving to perform the entire hoisting or lowering operation, and this alternative is contemplated particularly in those cases where it is found desirable to employ but a single trolley upon the bridge 15.

While this invention has been herein described by reference to a specific instance of its embodiment and use, it is intended that the protection to be afforded be not unnecessarily limited thereby, the intent being that such protection shall extend to the full limit of the inventive advance disclosed herein as defined by the claims hereto appended.

I claim:

1. In an apparatus for the handling of cargo, the combination with a ship having a deck of spaced, parallel, substantially horizontal runways secured to the ship above the deck, a traveling crane bridge extending from one of said runways to the other and adapted to move along the same, said runways being provided each with an elevatable section disposed opposite one another and adapted to engage and support the ends of said crane bridge in a preselected position, means for guiding said elevatable sections for vertical movement, means adapted to cause simultaneous vertical movement of said elevatable sections, and hoisting means mounted upon said bridge for movement thereover.

2. In an apparatus for the handling of cargo, the combination with a ship having a deck of an athwartship horizontal runway disposed above the deck, a second athwartship horizontal runway disposed above the deck, a traveling crane bridge extending longitudinally of said vessel from one of said runways to the other and adapted to move along the same, said runways being provided each with an elevatable section disposed opposite one another and adapted to engage and support the ends of said crane bridge in a preselected in-board position above the deck, means for guiding said elevatable sections for vertical movement from their overhead position as a part of said runways to a position adjacent the deck, means adapted to cause simultaneous vertical movement of said elevatable sections, and hoisting means mounted upon said bridge for movement thereover in a direction parallel to the longitudinal direction of the vessel.

3. In an apparatus for the handling of cargo, the combination with a ship having a deck of an athwartship horizontal runway disposed above the deck and forwardly of a hatch and adapted to extend beyond the side of the ship, a second athwartship horizontal runway disposed above the deck and aft of said hatch and adapted to extend beyond the side of the ship, a traveling crane bridge extending longitudinally of said vessel from one of said runways to the other and adapted for athwartship rolling engagement therewith, said runways being provided each with an elevatable section disposed opposite one another and adapted

5 to engage and support the ends of said crane bridge when in an inboard position above the deck of the ship, means for guiding said elevatable sections for vertical movement from their overhead position as parts of said runways to a position adjacent the deck, means adapted to cause simultaneous vertical movement of said elevatable sections, and downwardly extending hoisting means mounted upon said crane bridge for movement thereover in a direction parallel to the longitudinal direction of the vessel.

4. In an apparatus for the handling of cargo, the combination with a ship having a deck of spaced, parallel, substantially horizontal overhead runways secured to the deck, a traveling crane bridge extending from one of said runways to the other and adapted to move along the same, hoisting means mounted on said crane bridge, said runways being provided each with an elevatable section disposed opposite one another and adapted to engage and support the ends of said crane bridge in a preselected position, means for guiding said elevatable sections for vertical movement from their overhead position to a position adjacent the deck, and means adapted to be engaged and actuated by the hoisting means on said bridge for causing said elevatable sections to be raised or lowered simultaneously.

5. In an apparatus for the handling of cargo, the combination with a ship having a deck of spaced, parallel, substantially horizontal overhead runways secured to the deck, a traveling crane bridge extending from one of said runways to the other and adapted to move along the same, hoisting means including cable winding means mounted on said crane bridge for rolling engagement therewith, said runways each being provided with an elevatable section disposed opposite one another and adapted to engage and support the ends of said crane bridge in a preselected position, means for guiding said elevatable sections from their overhead position to a position adjacent the deck, and hoisting tackles associated with said elevatable sections adapted to be engaged and actuated by the cable winding means on said crane bridge for causing said elevatable sections to be raised or lowered in unison.

6. In an apparatus for the handling of cargo, the combination with a ship having a deck of spaced, parallel, substantially horizontal overhead runways secured to the deck, a traveling crane bridge extending from one of said runways to the other and adapted to move along the same, hoisting means mounted on said crane bridge, means associated with said runways and comprising oppositely positioned elevatable sections thereof for causing vertical movement of said crane bridge to and from the level of said runways, and a control platform for an operator mounted upon said crane bridge, said platform being movably secured to said crane bridge to permit the same to occupy a normal operation position extending below the bottom of said bridge and a stowed position above the operating position to permit said bridge to be brought close to said deck when stowed.

7. Cargo-handling apparatus for ships comprising in combination a pair of rails elevated above the deck of a ship, a hoist-carrying member bridging the same, a cargo hoist carried by the hoist-carrying member, driving mechanisms for the hoist-carrying member and the cargo hoist mounted on their respective units, rail sections intermediate the ends of said rails, and power driven elevating and lowering mechanism for sup-

porting said rail sections, and operable with the hoist-carrying member bridging the said rail sections to lower the rail sections, the hoist-carrying member and cargo hoist, together with the driving mechanisms therefore, below the level of the main portion of said rails.

8. Cargo-handling apparatus for ships comprising in combination a pair of rails elevated above the deck of a ship, a hoist-carrying member bridging said rails, driving mechanism for the hoist-carrying member mounted thereon, a cargo hoist and drive therefore carried by the hoist-carrying member, each rail being provided inter-

mediate its ends with a movable section of sufficient length to accommodate the hoist-carrying member, power driven mechanism for lowering the said movable rail sections below the horizontal plane of the main portion of the rails, together with the hoist-carrying member and the cargo hoist, and locking mechanism which is independent of said raising and lowering mechanism for locking the rail sections and hence the hoist-carrying member and cargo hoist in elevated position.

NILS PETER ERIK ANDERSEN.
